UNITED STATES PATENT OFFICE.

GEORG ZUELZER, OF CHARLOTTENBURG, NEAR BERLIN, GERMANY, ASSIGNOR, BY MESNE ASSIGNMENTS, TO THE CHEMICAL FOUNDATION, INC., A CORPORATION OF DELAWARE.

PROCESS OF MAKING MEANS FOR REDUCING BLOOD-PRESSURE.

1,399,535.

Specification of Letters Patent.

Patented Dec. 6, 1921.

No Drawing.

Application filed June 15, 1914. Serial No. 845,325.

To all whom it may concern:

Be it known that I, GEORG ZUELZER, a citizen of the German Empire, and residing at Charlottenburg, near Berlin, Germany, have invented a certain new and useful Improved Process of Making Means for Reducing Blood-Pressure, of which the following is a specification.

My invention relates to preparations for reducing the blood pressure, and to processes of making the same.

It is well known that albumoses are capable of considerably reducing the blood pressure. As the diminution in the pressure takes place very rapidly, however, the employment of albumoses for this purpose is attended with considerable danger to the health of the patient.

A primary object of my invention is to provide an improved preparation whose action on the blood pressure is less violent but occurs all the more continuously.

The following example will show how such a preparation according to my invention may be made:—

2 mg. bacterium coli, which have passed through a predetermined number of passages in the rabbit, are placed with standard or normal amboceptors for twelve hours in the refrigerator, then liberated from the serum by severe centrifuging and repeatedly washed, the bacteria being killed prior to centrifuging by the bactericidal action of the amboceptor serum. The washed sediment thus obtained is then put into 10 c. cms. 10% gelatin and is cooled after being mixed.

The preparation is then ready for use. The preparation is administered preferably by injecting it intramuscularly into the body of the patient.

The amboceptors above mentioned are those immunizing bodies found in blood serum which are formed by inoculation of an animal, such as the rabbit, monkey, guinea pig, with bacilli. They are thermostable bodies possessing two haptophor groups, namely, a cytophile and complementophile one of which groups unites with a

bacillus destroying thereby its vitality and releasing the endotoxin or albumose content 50 thereof.

Instead of using bacterium coli as described in the foregoing example, other saprophytic bacteria which readily yield endotoxin and which have been previously 55 admixed with an excess of normal amboceptors greater than may be produced by the activity of the bacterial content, may be employed.

I claim:

1. A preparation for reducing blood pressure, composed of gelatin containing non-pathogenic bacteria which form endotoxins charged with normal amboceptors, the amboceptor content being in excess of that 65 which may be produced through the activity of the bacterial content.

2. A preparation for reducing blood pressure, composed of gelatin containing bacterium coli charged with normal amboceptors, 70 the amboceptor content being in excess of that which may be produced through the activity of the bacterial content.

3. A process of making means for reducing blood pressure consisting in charging 75 non-pathogenic bacteria which form endotoxins with normal amboceptors, and mixing the same with gelatin.

4. A process of making means for reducing blood pressure consisting in charging 80 bacterium coli with normal amboceptors, and mixing the same with gelatin.

5. The process of making means for reducing blood pressure which comprises mixing non-pathogenic bacteria with normal ambo- 85 ceptors, refrigerating said mixture for about 12 hours, separating the bacteria and amboceptors from the liquid medium, washing the separated mass and incorporating said separated mass with gelatin.

6. The process of making means for reducing blood pressure which comprises mixing bacterium coli with normal amboceptors, refrigerating said mixture for about 12 hours, separating the bacteria and amboceptors from the liquid medium, washing the 95

separated mass and incorporating said separated mass with 10% gelatin.

7. The process of making means for reducing blood pressure which comprises mixing 2 mg. bacterium coli with normal amoceptors, refrigerating said mixture for about 12 hours, separating the bacteria and amoceptors from the liquid medium, washing the separated mass and incorporating said sep-

arated mass with 10 c.c. of 10% gelatin, and 10 finally cooling.

In testimony whereof, I affix my signature in the presence of two witnesses.

DR. GEORG ZUELZER.
